UNITED STATES PATENT OFFICE.

JOSEPH A. MARQUIS AND VICTOR E. GRAVES, OF SEATTLE, WASHINGTON, ASSIGNEES
OF ONE-THIRD TO HERMAN O. ZBINDEN, OF KING COUNTY, WASHINGTON.

CAN OPENER.

Application filed March 19, 1921. Serial No. 453,819.

To all whom it may concern:

Be it known that we, JOSEPH A. MARQUIS and VICTOR E. GRAVES, citizens of the United States and residing at Seattle, in the county 5 of King and State of Washington, have invented certain new and useful Improvements in Can Openers, of which the following is a specification.

The invention relates to an improvement 10 in can openers in the use of which the top of the can may be cut therefrom by an incision in the can side, whereby the full contents of the can may be readily and conveniently removed as an entirety.

15 In the drawings:—

Fig. 1 is a plan view showing the improved can opener in operative relation to the can.

Fig. 2 is a side view of the same with 20 portions of the can opener in vertical section.

Fig. 3 is a vertical section of the element support.

Fig. 4 is a section on line 4—4 of Fig. 3. 25 Fig. 5 is a longitudinal section of a modified form of support for the elements.

Fig. 6 is a transverse section of the same within the handle, and

Fig. 7 is an end view of the handle with 30 the parts in place.

In the preferred form, the can opener comprises a handle 1, which may be round or rectangular and within which is formed a longitudinal space 2 opening thru the forward end of the handle. Within the forward end of the space 2, at the forward end of the handle, is secured what may be termed a holder for the operative elements of the can opener. This holder comprises a hollow body 3 on the lower side of which is secured a block 4, and to the block and body, as by rivets 5 is secured a cutting blade 6. The forward end of the blade terminates in advance of the holder in a pointed cutter 7. 35 A centering guide is provided in the form of a bar 8 adapted to slidably fit in the opening in the holder 3 and having its forward end offset to provide the usual center 9.

The use of the improved can opener is 50 preferably thru forcing the point of the

center 9 thru the top of the can 10, while the can opener is in a vertical position, the rear end of the centering guide bearing against the rear end of the hollow handle in this operation. The can opener as a whole 55 is then turned downwardly and moved outwardly, the guide sliding to permit this movement until the cutting point 7 is below the top of the can. The handle is then driven forward toward the can forcing the 60 point 7 into the material of the can immediately above the top thereof, whereupon the can opener may be forced about the can, the point 7 severing the can material, to permit complete removal of the top off the can. 65

In the modified form shown in Figs. 5, 6 and 7, the holder for the operating elements is constructed of a single piece of material with the bottom plate thereof, as 11, forming the cutter proper, from which side walls 70 12 extend upwardly and are laterally offset as at 13 and then inwardly projected at 14 to form guiding recesses 15 to receive the centering guide 8. In this form as in the preferred form, the support is secured within the handle, which as here shown is circular and closed at the forward end except for slotted apertures 16 and 17 to permit the passage therethru of the guide and cutter. The operation of the modified form is the 75 same as that described in connection with the preferred form.

If desired and as preferred, the centering guide 8 may immediately in rear of the center point 9 thereof, be offset, as at 18 to provide a hook-like member serviceable for removing metal bottle caps and the like.

Claim:

A can opener, comprising a handle formed with a longitudinal central recess opening 90 through the forward end of the handle, a holder secured in said recess including a hollow body, a block secured thereto and a cutting blade secured to said block, the hollow body being positioned above the center line of the handle and the cutting blade below the center line thereof, said cutting blade being rigidly supported throughout its whole length beyond the cutting portion thereof by the block and the handle, and a 100

guide slidably mounted in said hollow body, the guide and the cutting blade being in parallel spaced relation, whereby when the 5 opener is positioned on a can, the guide will extend above the edge of the can and the block will form a spacing element between the guide and the cutting blade, so that the

blade will be positioned below the edge seam of the can for entirely severing the top from the can.

In testimony whereof we affix our signatures.

JOSEPH A. MARQUIS.
VICTOR E. GRAVES.
